UNITED STATES PATENT OFFICE

95,425

DESIGN FOR AN INTER-COMMUNICATING TELEPHONE SWITCH SET OR SIMILAR ARTICLE

Chester L. Herrick, Chicago, Ill., assignor to
Ampli-Phone Products Co., Inc., Chicago, Ill.,
a corporation of Illinois

Application January 31, 1935, Serial No. 55,174

Term of patent 7 years

To all whom it may concern:

Be it known that I, Chester L. Herrick, a citizen of the United States, and a resident of the city of Chicago, county of Cook, and State of Illinois, have invented a new, original, and ornamental Design for an Inter-Communicating Telephone Switch Set or Similar Article, of which the following is a specification, reference being had to the accompanying drawing, forming a part thereof.

On the drawing:

Figure 1 is a perspective view of an inter-com-

municating telephone switch set or similar article.

Figure 2 is a rear elevation thereof.

The hand set illustrated in dotted lines in the drawing forms an immaterial part of the design claimed, except in the combination as shown.

I claim:

The ornamental design for an inter-communicating telephone switch set or similar article as shown and described.

CHESTER L. HERRICK.
